COMBINATION SLACK, TIE AND COAT DISPLAY SUPPORT

John H. Batts and Judd F. Garrison, Grand Rapids, Mich.,
assignors to John Thomas Batts, Inc., Zeeland, Mich.

Filed Mar. 27, 1972, Ser. No. 238,754

Term of patent 14 years

Int. Cl. D6—08

U.S. Cl. D6—116

FIG. 4

FIG. 5

FIG. 6

FIG. 7

FIG. 8

FIG. 1 is a side elevation of a support embodying the design of our invention;

FIG. 2 is a plan view of the support;

FIG. 3 is a bottom plan view of the support;

FIG. 4 is an end elevational view of the support looking at right end thereof as viewed in FIG. 1;

FIG. 5 is an end elevational view of the support looking at the left end thereof as viewed in FIG. 1;

FIG. 6 is a cross-sectional view taken along plane VI-VI of FIG. 1;

FIG. 7 is a cross-sectional view taken along plane VII-VII of FIG. 1; and

FIG. 8 is a cross-sectional view taken along plane VIII-VIII of FIG. 1.

We claim:

The ornamental design for a combination slack, tie and coat display support, substantially as shown.
